AIR COMPRESSOR

Robert H. Hill, Fort Wayne, Ind., assignor to
Tokheim Oil Tank and Pump Company, Fort
Wayne, Ind., a corporation of Indiana

Application December 22, 1945, Serial No. 636,864

7 Claims. (Cl. 230—172)

1

This invention relates to a positive displacement air compressor.

The object of the invention is to produce a simple, compact air compressor which will operate quietly and efficiently at a relatively high compressor speed to deliver air with low pulsation, which compressor may be mounted on and direct connected to a standard electric motor, to form a readily portable unit.

In an illustrative embodiment of my invention, a compressor crank case is mounted directly on the end of a standard electric motor, and the compressor head mounted on that crank case. A cylinder is formed in the head, and a piston is reciprocated therein through a rod driven by an eccentric crank on the shaft of the electric motor. The piston is generally T-shaped in vertical section, with the stem of the T extending upwardly into a guide bore in the head, to guide the piston and permit it to be made substantially skirtless.

Intake and discharge passages are formed in the head, communicating with the cylinder through valves in the cylinder head. The valve elements are formed as light-weight disks, carried with their seats and valve springs in unitary assemblies pressed in suitable bores in the cylinder head.

The compressor desirably receives air through a screened silencing and intake tube, which is desirably positioned to form a handle for transporting the compressor. An inner intake screen is desirably kept moist, and the crank-case maintained under slight vacuum, by venting the crank case through a valved passage which opens to the intake passage outside such inner screen.

The relatively high speed of the compressor delivers air with minimum pulsation, but preferably I form an absorption chamber in the compressor base, and deliver air therefrom through a fitting which also embodies an overload relief valve and a manual relief and clean-out valve.

While my compressor is designed for association with an electric motor, and is so shown in the accompanying drawing, it may be driven by other sources of power, as by substituting an internal combustion engine for the electric motor.

The accompanying drawings illustrate my invention. In such drawings: Fig. 1 is an end elevation of a compressor embodying my invention; Fig. 2 is a side elevation of the compressor shown in Fig. 1, with the crank case, head, and outlet fitting shown in section; Fig. 3 is a horizontal section through the head of the compressor shown in Figs. 1 and 2, on the line 3—3 of Fig. 4; Fig. 4 is a vertical section on the line 4—4 of

2

Fig. 3, showing the valve units; and Fig. 5 is an elevation of the connecting rod and eccentric, with the big end of the rod shown in section.

The compressor is shown in the drawings as associated with an electric motor 10. The crank case 11 of the compressor is mounted directly on the end of the motor 10, and the compressor head 12 is mounted on the crank case 11.

An eccentric 15 is mounted on the shaft 16 of the motor 10, conveniently by a key 17 locked in the key way of the shaft 16 by a set screw 18. The big end of the connecting rod 20 is mounted on the eccentric 15, preferably by needle bearings 21, and is held against axial movement by counterweight disks 22 attached against the sides of the eccentric 15 as by bolts 23. The small end of the connecting rod 20 is connected to the piston by a sleeve bearing and a piston pin 26. Desirably, the piston pin 26 is locked to the piston by a cross pin 27.

The piston is formed of a carrier 25 and a head 30. The carrier extends upwardly to form a hollow guide rod 28 slidably in a central guide bore in the head 12. The piston head 30 is mounted on the carrier 25, desirably by locking it against a suitable shoulder with a lock nut 31 which is pinned in locked position. The piston head 30 is relatively short, with its side walls of sufficient length to form a ring band and some bearing surface against the cylinder 35, but with substantially no skirt. The use of the guide 28 fully prevents piston wobble without the necessity for any extended skirt on the piston. This permits the piston and cylinder to be short so that the cylinder can conveniently be formed in the head; and reduces the weight of the moving parts to facilitate operation at the relatively high speed (for a compressor) of a standard electric motor 10.

An intake passage 37 is formed in the head, and to receive one end of an intake tube 38. The passage 37 is shouldered so that a filter screen 39 may be received between the shoulder and the inner end of the inlet tube 38. Desirably, the screen 39 is formed of two layers of wire mesh, with an intervening layer of felt. An additional screen 40 may be placed in the open end of the tube 38, and if desired the tube 38 may contain silencing material, but I have found that the compressor operates with remarkable quietness without the necessity for any such silencing material. The outer end of the tube 38 is secured to the motor 10, as by a bracket 41, so that the tube may serve as a handle for transporting the compressor.

The intake passage 37 leads to a pair of intake

valves. Each such valve is formed in an annular body 50, shaped to provide a valve seat 51. A light-weight disk-shaped valve element 52 is associated with the valve seat 51, and its displacement is desirably limited by a raised central portion of a holder 54, which portion may also serve to center a valve spring 53 supported by the holder 54. The valves are formed as units, and are pressed into bores in the top wall of the cylinder 35.

The outlet valves 55, which are similarly pressed in place, are similar in construction to the inlet valves 50-54 and have similar disk valve-elements 56, but may be of slightly smaller size. An outlet passage 57 leads from the outlet valves 55, and is connected to a pipe 58.

The valve disks 52 and 56 are of light weight and of low inertia. Preferably, they are of spring steel about six to eight thousandths (0.006 to 0.008) of an inch thick, to give adequate lightness with sufficient strength for long service.

A vent passage 42, drilled in the crank case and head, leads from the crank case to communication with the intake passage just outside the screen 39. A seat for a valve in this vent passage 42 is formed in a chamber 43 in the upper surface of the crank case, and a disk valve 44 is positioned in the valve chamber 43 against the seat when the compressor is assembled. The head 45 of a screw in the lower surface of the head 12 overlies the valve disk 44 to limit its displacement.

The valved crank-case vent maintains the case under slight vacuum and leads normally escaping oil vapor to the intake, to moisten the filter screen 39. Such oil vapor also supplements the splash system of lubrication, especially when high pressure operation tends to dry the cylinder walls, for under those conditions oil-vapor escape tends to increase, and this is delivered through the intake for top-cylinder lubrication.

The cylinder head is secured to the crank-case, as by stud bolts, in a plane below the cylinder 35. The cylinder 35 and the bore for the piston guide 28 are thus formed in an integral head, for permanent alinement. This arrangement also serves to place the compression space within the integral head, where adequate air cooling may be obtained by a single set of fins carried by the head.

The compressor is carried by a base 60, preferably by mounting the motor 10 on a suitable bracket 61 on that base 60. The base 60 is formed to provide an absorbing chamber 65, to which the pipe 58 leading from the outlet passage 57 of the compressor is connected.

The compressed air is delivered from the absorbing chamber 65 through an outlet connection 66 of a fitting 70, which also houses an over-load relief valve and a clean-out and manual-relief valve. The over-load relief valve is formed in a boss 73 on the fitting 70. It has a plunger 72 spring-pressed inwardly to urge its bluntly tapered inner end against a seat formed in the fitting 70, to normally close a passage 74 which is in open communication with the absorbing chamber 65.

A clean out tube 75 leads from near the bottom wall 64 of the absorbing chamber 65 upwardly through the fitting 70 out of communication with the normal air delivery passage, to a valve 76 which is normally held in closed position by the spring 77. A head on the stem of the valve 76 may be manually depressed to open the valve 76

and release air through the clean-out tube 75 to a relief opening 78. Normal operation of the relief valve 76, as when starting the compressor, will automatically give clean-out action to remove any accumulation of moisture and oil condensation.

My compressor may be direct connected through the connection 66 to a device requiring compressed air, such for instance as a spray gun, a grease gun, etc.

The design of my compressor, and the low weight of its moving parts, contribute to make it operate quietly and efficiently at high speed, as at the standard high speed of the electric motor 10, or even at substantially higher speed. Oil vapor unavoidably escaping from the crank case is carried by the vent-passage to the intake and utilized to moisten the filter and for top lubrication, especially when operation at high pressures tends to reduce normal top-cylinder lubrication. Air delivery is smooth and prompt, to provide air at high pressure, or in greater quantities at lower pressure, as its use may require.

I claim as my invention:

1. An air-compressor, comprising a motor having a frame and a power shaft, a compressor crank case mounted on said frame, an eccentric crank mounted on said shaft within said crank-case, a compressor head on said crank-case, a cylinder formed in said head, a piston in said cylinder, a piston rod connecting said piston to said eccentric crank, a flat base supporting said motor and compressor, said base having spaced upper and lower walls joined at their edges to form a flat absorption chamber substantially co-extensive with the base, said discharge passage being connected in open communication with said absorption chamber, and an air delivery fitting on said absorption chamber.

2. An air-compressor, comprising a motor having a frame and a power shaft, a compressor crank case mounted on said frame, an eccentric crank mounted on said shaft within said crank-case, a compressor head on said crank-case, a cylinder formed in said head, a central guide-bore in said head at the end of said cylinder, a piston in said cylinder having a guide slidably received in said guide-bore, a piston rod connecting said piston to said eccentric crank, a screen in said intake passage, a vent passage leading from said crank case and discharging to said intake passage outside said screen, and a check valve in said vent passage opening toward said intake passage, said crank case being closed save for said vent passage.

3. An air-compressor, comprising a motor, a compressor including a piston and cylinder, an eccentric crank connected for operation at motor speed to reciprocate said piston through short strokes in said cylinder, a flat base supporting said motor and compressor, a flat absorption chamber formed in said base, means connecting the discharge from said compressor in open communication with said absorption chamber, and an air delivery fitting on said absorption chamber.

4. An air-compressor, comprising a motor having a frame and a power shaft, a compressor crank case mounted on said frame, an eccentric crank mounted on said shaft within said crank-case, a compressor head on said crank-case and having an intake passage, a cylinder formed in said head, a piston in said cylinder, a piston rod connecting said piston to said eccentric crank, a screen in said intake passage, a vent passage

leading from said crank case and discharging to said intake passage outside said screen, and a check valve in said vent passage opening toward said intake passage, said crank case being closed save for said vent passage.

5. An air-compressor, comprising a crank case and a crank mounted for rotation therein, a compressor head on said crank case, a cylinder formed in said head, a piston connected to the crank for reciprocation in the cylinder, an intake passage formed in said head, a crank-case vent passage in said head extending from said intake passage through the face of the head joint with said crank case, a connecting vent passage in said crank case, a valve chamber in said vent passages at said joint, and a check valve in the valve chamber opening toward said intake passage, said crank-case being closed save for said valved vent passage.

6. An air-compressor, comprising a crank-case, a shaft mounted for revolution therein, an eccentric sleeve mounted on said shaft, a cylinder supported on said crank-case, a piston therein, a connecting rod having its big end rotatably received on said eccentric sleeve, counterweight disks secured on the ends of said eccentric sleeve and preventing axial displacement of said connecting rod therefrom, said connecting rod being connected to reciprocate said piston, and valved intake and discharge passages to and from said cylinder.

7. An air compressor, comprising a crank case and a crank mounted for rotation therein, a compressor head on said crank-case and having an intake passage, a cylinder formed in said head, a piston in said cylinder, a piston rod connecting said piston to said eccentric crank, a screen in

said intake passage, a vent passage leading from said crank-case and discharging to said intake passage outside said screen, and a check valve in said vent passage opening toward said intake passage, said crank case being closed save for said vent passage.
